UNITED STATES PATENT OFFICE.

DANIEL GIMBEL AND ALBERT DECKER, OF CHICAGO, ILLINOIS.

DESIGN FOR A KNEE-PROTECTOR.

SPECIFICATION forming part of Design No. 30,552, dated April 11, 1899.

Application filed March 8, 1899. Serial No. 708,037. Term of patent 3½ years.

To all whom it may concern:

Be it known that we, DANIEL GIMBEL and ALBERT DECKER, citizens of the United States, residing at Chicago, in the county of Cook and State of Illinois, have invented and produced a new and original Design for Knee-Protectors, of which the following is a description, reference being had to the accompanying drawings, forming a part of this specification.

Figure 1 is a perspective view of a knee-protector, showing our new design; and Fig. 2 is a front elevation of the same.

As shown in the drawings, the leading features of our design consist of a rectangular figure having approximately square corners *a* on its lower face and rounded corners *b* on its upper face. Forming a part of the upper face *C* are concave portions *c*, which extend from the front edge *d* through a part of the

cross-diameter of the knee-protector. Said concave portions have their greatest depth at the front edge *d* and gradually taper toward the rear edge *e*. Between said concave portion is a ridge or convex portion *f*. Supporting the knee-protector at the four corners are casters or rollers *g* of the usual form.

Having thus described our design, what we claim as new, and desire to secure by Letters Patent, is—

The design for a knee-protector, substantially as herein shown and described.

In testimony whereof we affix our signatures in presence of two witnesses.

DANIEL GIMBEL.
ALBERT DECKER.
